UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of Design No. 14,034, dated July 3, 1883.

Application filed May 4, 1883. Term of patent 3½ years.

To all whom it may concern:

Be it known that I, PAUL PIGNOT, of Yonkers, in the county of Westchester and State of New York, have invented a new and original 5 Design for Carpets, of which the following is a specification.

The accompanying photograph illustrates a face view of my new design for carpets.

This invention relates to a new design for 10 carpets and analogous fabrics; and it consists of the new configuration of groups and figures that make up the groundwork of the carpet.

The carpet which is shown in the accompanying photograph is divided by two narrow bands, *a* and *b*, into three stripes, A.B.C. The band *a* is ornamented by the representation of 15 a ribbon, *d*, which is folded or looped into an undulating form, and which extends into the stripe A at intervals, as shown. The band *b* is ornamented with a row of rings, within each 20 of which appears a smaller ball, somewhat resembling in appearance the echinus in architecture. The narrower of the three stripes into which the carpet is divided by the bands 25 *a b* is at one side of the carpet and is marked A, and is decorated with uprightly-extending conventional leaves, as indicated in the photo-

tograph. The stripe B, which is between the bands *a b*, represents a narrow section of landscape, showing roses *e*, violets *f*, and other flowers in the neighborhood of the representation of a small pond, *g*, above which the sky can be seen. The main portion C of the carpet is also ornamented with many flowers, *l*, appearing to grow near a fence-like structure, 35 *h*, behind which can be seen a field, *i*, of grain, and over which are the branches *j* of a tree. Between the grain and the branches the sky can be seen, the entire effect of this arrangement of flowers, tree, and grain being particularly rich, especially if represented in appropriate colors. 40

I claim—

1. The design for carpets, consisting of the stripe C, having the figures *h i j l*, substantially as shown. 45
2. The design for carpets, consisting of the stripe A, band *a*, with ribbon *d* thereon, stripe B, with figures *e f g*, band *b*, and stripe C, with figures *h i j*, and *l*, substantially as shown.
